Primary Examiner — Garth Rademaker
Assistant Examiner — Laura H Yu

(57) **CLAIM**

The ornamental design for an anti-cutting hand device for tape dispenser, as shown and described.

DESCRIPTION

FIG. 1 is a front, bottom perspective view of a first embodiment of an anti-cutting hand device for tape dispenser, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the first embodiment of the anti-cutting hand device for tape dispenser, shown in an environment of use;

FIG. 10 is a front, bottom perspective view of a second embodiment of the anti-cutting hand device for tape dispenser;

FIG. 11 is a rear, top perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is another perspective view of the second embodiment of the anti-cutting hand device for tape dispenser, shown in an environment of use.

The broken lines in FIGS. 9 and 18 illustrate environment and form no part of the claimed design.

1 Claim, 18 Drawing Sheets
